UNITED STATES PATENT OFFICE.

AXEL GUSTAF EMANUEL HULTGREN, OF GOTTFENBOORG, SWEDEN, ASSIGNEE TO
AKTIEBOLAGET SVENSKA KULLAGERFABRIKEN, OF GOTTFENBOORG, SWEDEN,
A CORPORATION OF SWEDEN.

MEANS FOR REMOVING HARDENED ANNULAR BODIES FROM THE HARDENING LIQUID.

1,308,077.

Specification of Letters Patent.

Patented July 1, 1919.

Application filed December 22, 1917. Serial No. 208,494.

To all whom it may concern:

Be it known that I, AXEL GUSTAF EMANUEL HULTGREN, a subject of the King of Sweden, residing at Gottenborg, Sweden, have invented certain new and useful Improvements in Means for Removing Hardened Annular Bodies from the Hardening Liquid, of which the following is a specification, reference being had to the drawing accompanying and forming a part thereof.

This invention relates to means for removing hardened annular bodies from the hardening liquid, and particularly to such means in combination with a hardening device in which the rings roll on an incline into the hardening liquid.

The invention consists, chiefly, in so forming the lower part of the incline that the rolling motion of the rings ceases and the rings are caused to slide in a lying position. The removal of the rings from the hardening liquid is, preferably, performed by a simple continuous conveying mechanism.

In the drawing, one form of the means for carrying out the invention is shown, Figure 1 is a side view of the incline and the device for removing the hardened articles from the hardening liquid. Fig. 2 is a plan view thereof. Fig. 3 shows, on an enlarged scale, the lower part of the incline. Fig. 4 shows transverse sections on the lines A—B, O—C, O—D, O—E, O—F, O—G, O—H and O—J of Fig. 3. The line M—M of Fig. 4 corresponds to the line denoted by the same letters in Fig. 1 and serves to illustrate the relative position of the several sections in the vertical direction. Fig. 5 is a sectional view on line 5—5 of Fig. 2, and Fig. 6 is a detail perspective view of a modified form of track for the ring bodies.

In the drawing, 1 designates the incline on which the rings 2 to be hardened are caused to roll into the hardening liquid. The lower part of the incline, which is immersed in the hardening liquid, is shown bent or curved laterally and has, preferably, the form of a laterally inclined screw thread, as shown in Fig. 4.

Fitting closely to the curved part of the incline and forming a continuation thereof is an extension forming an angle with the former. In order to save room, the said angle is, preferably, about 180°, if viewed in plan.

The curved part of the incline serves to 55 check the rolling motion of the rings, to which end it is bent upward to the required height, as shown at 4. If desired, it may be bent so as to form a roof. The curved part of the incline also serves to tilt the rings and 60 to impart to them a sliding movement toward the side.

After the rings have begun to slide, they are guided by the upstanding edges of the extension or lower part of the incline down 65 to the end thereof. The said end 5 bears on the transport band 6 of a conveying mechanism and is provided with a notch or aperture 7 (Fig. 2) through which pass the pins 3 or the like of the transport band. When 70 the hardened rings 2 reach the said notch in the incline, they are grasped by the pins 3, one after the other, and removed from the hardening liquid and placed on an inclined track 9, from whence they are brought to the 75 collecting place.

The upper part of the incline 1 is, suitably, provided with guiding grooves for the rings, as shown in Fig. 2. Said grooves may be formed by U-irons 10 or the like. 80

If desired, the changing of the rolling motion of the rings into a sliding motion may be afforded otherwise than hereinbefore described, for instance by extending the U-irons 10 into the hardening liquid and twisting the lower part of said irons in their longitudinal direction so that their side flanges obtain a gradually increasing inclination with respect to the bottom surface of the incline 1. It is obvious that the rings 2 will 85 thus be caused to lean, more and more, against the said bottom surface, so that they will finally turn over and slide in a lying position on the incline, which in such case may be rectilinear in shape. 95

What I claim is:—

1. In a hardening device for annular bodies, the combination of an incline on which the bodies roll into the hardening liquid, the lower part of said incline being 100 formed so as to cause the rolling bodies to tilt and slide on the incline in a lying position, and means for continuously removing the hardened bodies from the hardening liquid, substantially as described. 105

2. In a hardening device for annular bodies, the combination of an incline on which the bodies roll into the hardening

liquid, the lower part of said incline being bent laterally so as to form a laterally inclined screw thread, said lower part of the incline being provided with an extension 5 forming an angle with the upper part of the incline, by which the rolling bodies are caused to tilt and slide on the incline in a lying position, and means for continuously removing hardened bodies from the hardening liquid, substantially as described.

3. In a hardening device for annular bodies, the combination of an incline having partition walls between which the bodies roll into the hardening liquid, the lower parts of 15 the said partition walls having a gradually increasing inclination against the bottom surface of the incline by which the rolling bodies are caused to tilt and slide on the incline in a lying position, and means for con-

tinuously removing the hardened bodies 20 from the hardening liquid, substantially as described.

4. In a hardening device for annular bodies, the combination of an incline on which the bodies roll into the hardening 25 liquid, the lower part of said incline being formed so as to cause the rolling bodies to tilt and slide on the incline in a lying position, and a conveying mechanism comprising a transport band, said transport band being provided with pins passing through an aperture in the lower end of the incline, whereby the said pins catch the annular bodies and remove them from the hardening liquid, substantially as described.

30 In testimony whereof I affix my signature.

35 AXEL GUSTAF EMANUEL HULTGREN.
